United States Patent Office.

PHILIPPE KOCH, OF NEW HAVEN, CONNECTICUT.

Letters Patent No. 68,089, dated August 27, 1867.

IMPROVED WOODEN PAVEMENT.

The Schedule referred to in these Letters Patent and making part of the same.

TO ALL WHOM IT MAY CONCERN:

Be it known that I, PHILIPPE KOCH, of the city and county of New Haven, in the State of Connecticut, have invented a new and useful Improvement in Blocks for Paving Streets, Roads, &c.; and I do hereby declare that the following is a full, clear, and exact description of the construction, character, and operation of the same, reference being had to the accompanying drawing, which makes part of this specification, which drawing is a perspective view of one complete block and a portion of an adjoining one, showing the form of the upper surface and the manner of connecting or joining the blocks when set.

My improvement consists in making square or other rectangular blocks of wood of suitable length (with the grain of the wood) to suit the character of the street or road, and of such horizontal dimensions as shall be found most convenient and serviceable in each case, and suitably bevelled upward and downward for a suitable distance from the ends, and to be set in the ground or sand, the same as prepared stones are, (as of the Belgian pavement, for example,) and the upper surface cut to a suitable depth into squares or rectangular forms, so that the spaces may be filled with dirt to make it easy and safe for horses to travel upon, as they will not slip.

I make the block for paving of white oak, or any other suitable wood, sawed, split, or cut into square blocks, as represented in the drawing, of suitable dimensions to be convenient for setting or laying the pavement, say from six to twelve inches square, in the horizontal directions (or across the grain) and from eight to ten inches in the vertical line, (in the direction of the grain,) according to the character of the ground or use to be made of the street or road; and I cut or divide the upper surface of each block into small squares, say from one to two inches square, as represented at A A, &c., cutting the spaces both ways from one-half to three-fourths of an inch in width, as represented at b and c, and from one to two inches in depth, as represented at d and e, which may be readily done by a ploughing or grooving machine, by causing the blocks to pass through in any convenient manner to suit the design of the work; and I bevel the upper end, on all sides, of each block, as represented at g, h, and k, so that where two blocks, as B and C, come together, they will leave a space at the top, as represented at g g g, of about the same dimensions at the extreme top as the spaces or channels which are cut in the blocks; and I also bevel the block, on all sides, at the bottom or lower end, as represented at D, E, F, and G, so that they may be forced into the ground more readily, and also fit and set more steadily in their proper positions.

Having made the blocks, as before described, I prepare the street or road in the same way as for paving with prepared stones, and then set the blocks in the ground or sand side by side, as shown at B and C, and set them down the same as stone blocks, and then fill the channels or spaces b, c, d, e with sand in the usual way, so that if there should be any looseness between the blocks (as B and C) the sand will run down the inclined sides, as at g g g, between the blocks so as to fill the spaces perfectly solid, so as to bind and always keep them steady and firm. By the action of the feet of the horses and wheels of the carriages, the corners and edges of the small square surfaces will be forced or bruised off and broomed down so as to confine the sand in the grooves, which will give the pavement a general evenness, with a slight wavering, so as to be easy to the horses' feet, and will not be slippery. Instead of ploughing the grooves parallel with the sides of the block, they may be cut diagonally, and the blocks may be made as elongated rectangles or hexagons, but I prefer the square.

I am aware that wooden blocks set in iron frames have been used in England, as described in Newton's Journal, first series, volume 9, pages 197 to 202; also, that Stephen Cary obtained a patent, dated February 3, 1841, for using large quadrangular blocks with their vertical sides cut alternately concave and convex, and, although the blocks were so bevelled upward as to leave a space around them, yet each block was left smooth on the whole of its upper surface, which caused horses to slip so badly that it was discarded; also, that Samuel Nicolson obtained a patent, dated August 8, 1854, for the use of small blocks set alternately with blocks of about one-half their length, so as to form recesses to be filled with gravel and tar, or other cement, to cement the gravel, and also the small wooden blocks, together, or (he says) the blocks may be secured together by wooden pins, and he uses tarred paper, boards, or lime mortar to prepare the foundation on which his pavement is to rest. This (if the small blocks were not irregularly forced into the ground so as to destroy the evenness of the road) would make the pavement so costly as to forbid its use. I therefore do not claim either of these methods as my invention, nor do I desire to use either; but what I claim as my invention, and desire to secure by Letters Patent, is—

The construction and arrangement of wooden paving-blocks in the manner and for the purpose herein described and set forth.
